UNITED STATES PATENT OFFICE

MIGUEL ANGEL LAMOGLIA, OF CIENFUEGOS, CUBA

PENCIL

Application filed May 3, 1930. Serial No. 449,614.

My present invention has reference to a combination article, and my object is the provision of a combined handle for safety razors, a compartment for the separated 5 parts of the razor, a compartment for razor blades and a writing implement designed for use when the razor is not employed.

A further object is the provision of a combination article for this purpose which shall 10 be of a simple construction, ornamental, small in size, successfully employed either as a handle for safety razors or as a writing implement and wherein novel feed means is provided for the lead or the pen point of the 15 writing implement.

To the attainment of the foregoing the invention consists in the improvement herein-after described and definitely claimed.

In the drawings:

20 Figure 1 is a side elevation of the device when employed as a writing implement.

Figure 2 is a longitudinal sectional view therethrough.

Figure 3 is an elevation of the device employed as a holder for safety razor blades.

25 Figure 4 is a sectional view approximately on the line 4—4 of Figure 1.

Figures 5, 6, 7 and 8 are transverse sectional views respectively on the lines 5—5, 6—6, 30 7—7, and 8—8 of Figure 2.

The improvement is preferably constructed of metal and is highly polished or may be otherwise ornamental. The improvement comprises a main and preferably rectangular 35 hollow portion 1, a tubular portion 2 connected or formed with one end of the body 1, a hollow nose end 3 that has a slip joint and flexible connection with the ends of the part 2 and a nut 4 for closing the rounded outer 40 end 5 of the body 1.

As disclosed by Figure 2 of the drawings the body 1 provides a compartment for a case containing safety razor blades 6, and the head guard and stem of a safety razor blade which 45 rests on the case for the razor blade, the case resting directly on the division wall 7 between the body 1 and the tubular portion 2.

The nut 4 is round in plan and includes a central enlarged portion which is knurled, 50 as at 8, while the ends or portions of the nut

extending from the knurled center thereof are threaded so that either of the same may be screwed in the widened and round end of the body 1. On the face of one of the threaded portions there is formed an extension 9 55 that has a threaded socket 10 designed to have screwed therein the shank 11 on the head 12 of the safety razor to compress against the head the guard 13 and likewise to hold the razor blade between the guard and 60 head. On the outer end of the second threaded portion of the nut 4 there is a tubular extension 14 provided with a socket for a rubber eraser 15.

The tubular portion 2 of the improvement 65 has one of its sides formed with a longitudinally arranged slot or opening 16 and one of the side walls provided by this opening is formed with a rack surface 17. Communicating with a central opening in the end of the nose 3 and extending inward thereof to contact with the partition 7 there is a guide tube 18 for a pencil lead 19 or for a pen point. The tube 18 is provided on one of its sides with a longitudinal slot 20, and in the tube 19 70 there is arranged and frictionally received a feeder tube 21. The lead 19 or the pen point is received in the feeder tube. The feeder tube at its upper end is provided with an arched spring handle 22 that has an outer head 23 and an inner lug 24 which are formed on the outwardly extending angle end 25 of the said element 22. The element 22 being of 75 spring metal exerts a pressure toward the rack surface 17 to bring the end 25, between the head 23 on the stop element 24 into the notches provided by the teeth on the said rack 17 and whereby, by merely swinging the spring member 22 from between certain 80 of the teeth and permitting the same to engage between other teeth the pencil lead or other implement 19 may be moved into or outward of the nose and the tube or sleeve 85 18 therein.

When the device is employed as a pencil 90 the razor is housed in the body 1 as disclosed by Figure 2 of the drawings but when the razor is desired for use the lead or like element 19 is drawn into the nose end of the handle and the nut 4 is unscrewed from the 95 100

body 1 to permit of the withdrawal of the razor and the blade. The nut is again then reversely screwed in the part 5 of the body 1 so that the shank 11 may be screwed into 5 the threaded socket 10 and the razor thus held for convenient use.

The construction of the improvement and the advantages thereof will, it is thought, be understood and appreciated by those skilled 10 in the art to which the invention relates so that further detailed description will not be required. Obviously I do not desire to be restricted to the precise details herein set forth and, therefore, hold myself entitled to 15 make such changes therefrom as fairly fall within the scope of what I claim.

Having described the invention, I claim:

1. An article for the purpose set forth comprising a handle, one end of the handle 20 being provided with a tubular extension that merges into a nose end having a central opening, a longitudinally slotted sleeve mounted in the tubular extension with one end in communication with the central opening in 25 the nose, a split spring feeder tube frictionally received in the sleeve and designed to hold the lead, an arched spring arm on the tube received through the slot of the sleeve, said tubular extension having a longitudinal 30 slot therein, one of whose walls is formed with a rack, and said arm having a straight arm to engage said rack.

2. An article for the purpose set forth comprising a handle, one end of the handle being 35 provided with a tubular extension that merges into a nose end having a central opening, a longitudinally slotted sleeve mounted in the tubular extension with one end communicating with the central opening, a split 40 spring feeder tube frictionally received in the tube and designed to hold the lead, an arched spring arm on the tube received through the slot of the sleeve, said tubular extension having a longitudinal slot therein 45 one of whose walls is formed with a rack, said arm having a straight end to engage with said rack, a handle on the outer end of said extension of the arm, and a stop element on said extension inwardly of the 50 handle.

In testimony whereof I affix my signature.

MIGUEL ANGEL LAMOGLIA.
